D. F. FESLER

FILTER

Filed July 3, 1922

Inventor
Douglas F. Fesler
William Bradbury
McCabb & Pierce Attn:

UNITED STATES PATENT OFFICE.

DOUGLAS F. FESLER, OF CHICAGO, ILLINOIS, ASSIGNOR TO THE BASSICK MANUFACTURING COMPANY, OF CHICAGO, ILLINOIS, A CORPORATION OF DELAWARE.

FILTER.

Application filed July 3, 1922. Serial No. 572,711.

My invention relates to improvements in filters, and is particularly concerned with, though not limited to, improvements in filters adapted to be used for filtering the fuel passing from the supply tank to an internal combustion engine.

The objects of this invention are:

First.—To provide a filter of the character described, comprising means for collecting and holding the dirt and water usually found in commercial gasoline and other fuels consumed by internal combustion engines;

Second.—To provide a filter of the character described, comprising a receptacle having a transparent wall so that the accumulation of impurities can be seen;

Third.—To provide a filter, such as described, so constructed as to permit easy and quick removal of the accumulated sediment, and replacement of the filter element;

Fourth.—To provide a filter of the character described which is constructed so that it can be easily and quickly inserted in the fuel line from the supply tank to the engine, and

Finally.—To provide a filter which is simple in construction, and economical to manufacture.

Other objects will appear as this description progresses, reference being had to the accompanying drawings, in which

Figure 1 is a transverse section, taken on line 1—1 of Figure 2, and

Figure 2 is a vertical section taken on line 2—2 of Figure 1, the filter in this figure being shown attached to the upper portion of a vacuum tank.

In both views of the drawings, similar reference characters will be used for referring to similar parts.

In the preferred embodiment of my invention, I provide a cup-shaped receptacle 5, the upper end of which is open and provided with an outwardly extending flange 6, for a purpose which will later be referred to. A number of scallops 7, cut in the inner side of the upper end of the receptacle, form a plurality of projections 8 which extend inwardly from the edge of the open end of the receptacle, and provide supports for a filter element, comprising the disc 9 having a central opening 10 and the bowed wire supporting members 11, the inner ends of which extend through the disc 9 and are

riveted thereto. A suitable filter bag 12, which is preferably made of chamois, is stretched over the supporting wires 11, and the edge of the open end thereof is confined between the edge of the disc and a U-shaped metal clamping strip 13, which entirely encloses the edge of the disc 9.

The cap 14, for the receptacle 5, comprises a depending flange 15 and a central boss 16, forming an annular chamber 17, which communicates with the receptacle 5 through the spaces or scallops between the inwardly extending projections 8, the flange 15 having a plurality of scallops 18 formed in its inner wall, which are adapted to be brought into registry with the scallops 7 formed in the receptacle.

To secure the cap 14 to the receptacle, I provide a threaded extension 19 on the flange 15, with which the threaded ring 20, having the inwardly extending flange 21, contacts. The flange 21 extends inwardly to a position beneath the outwardly extending flange 6, so that when the ring 20 is screwed onto the extension 19, the receptacle is clamped to the cap. I prefer to make use of a gasket 22 of cork or other suitable material for sealing the joint between the cap and the receptacle.

A threaded bore 23, extending inwardly from the outer face of the cap 14, provides means for making a connection with an elbow 24, which is connected with one end of a pipe 25 leading from the gasoline supply tank. The bore 23 communicates with the annular chamber 17 through a plurality of smaller bores 26 formed in the central boss 16.

The boss 16 is provided with a central projection 27 which extends through the opening 10 in the disc 9, the joint between the disc and the boss 16 being sealed by a gasket 28 of felt or other suitable material.

A bore 29, formed in the projection 27, communicates with a bore 30 passing through the bridge 31, extending from the boss 16 to the flange 15 of the cap, and outwardly through a bracket 32, which is formed integrally with the cap, and which ends in a ring or eye 33, which is adapted to be brought into registry with the hollow boss 34 which forms the inlet to the vacuum tank 35, a portion only of which is illustrated. The ring 33 is clamped to the boss 34 by means of the plug 35, the inner end

of which is threaded into the boss 34. This plug has a central bore 36 and an annular groove 37 formed in the periphery thereof, which communicate through a plurality of transverse bores 38. If desired, a gasket 39 may be used for sealing the joint between the plug and the ring 33.

While I have described the details of construction of the preferred embodiment of my invention, it is to be clearly understood that my invention is not limited to these details, but is capable of other adaptations and modifications within the scope of the appended claims.

Having thus described my invention, what I claim is:

1. A filter comprising a receptacle having a plurality of projections extending inwardly from the edge of the open end thereof, a filter element comprising a disc, the edge of which rests upon the inner ends of said projections, said disc having a central opening, a filter bag depending from said disc into said receptacle, and a cap for said receptacle having a central boss and a flange forming an annular chamber communicating with said receptacle through the spaces between said projections, said boss having an inlet bore formed therethrough communicating with said annular chamber and a projection extending through said central opening and having an outlet bore formed therein.

2. A filter comprising a receptacle having a plurality of projections extending inwardly from the edge of the open end thereof, a filter element supported by the inner ends of said projections and projecting into said receptacle, and a cap for said receptacle

having a central boss and a flange forming an annular chamber communicating with said receptacle through the spaces between said projections, said boss having an inlet bore communicating with said annular chamber and an outlet bore communicating with the interior of said filter element.

3. A filter element comprising an imperforate disc having a central opening, a plurality of bowed wires, the ends of which are secured to said disc adjacent the edge thereof, a filter bag held in position by said bowed wires, and means for securing the edge of the open end of said filter bag directly to the edge of said disc.

4. A filter element comprising an imperforate disc having a central opening, a plurality of bowed supporting wires, the free ends of which are secured to said disc adjacent the edge thereof, a filter bag stretched over said bowed wires, and means carried by said disc and forming a unitary structure with said disc, wires and bag for securing the open end of said filter bag directly to the edge of said disc.

5. A filter comprising a receptacle having a plurality of projections extending inwardly from the edge of the open end thereof, a chambered filter element having a flange resting upon the inner ends of said projections, the space between said projections providing inlet passages to said receptacle, and means communicating with the interior of said filter element to provide an outlet therefrom.

In witness whereof, I hereunto subscribe my name this 30th day of June, 1922.

DOUGLAS F. FESLER.
